UNITED STATES PATENT OFFICE.

ALFRED E. DETWILER, OF MILWAUKEE, WISCONSIN, ASSIGNOR TO THE MILWAUKEE GAS STOVE COMPANY, OF SAME PLACE.

STOVE-DOOR HINGE.

SPECIFICATION forming part of Letters Patent No. 553,484, dated January 21, 1896.

Application filed February 12, 1894. Serial No. 499,840. (No model.)

To all whom it may concern:

Be it known that I, ALFRED E. DETWILER, of Milwaukee, in the county of Milwaukee and State of Wisconsin, have invented certain new and useful Improvements in Stove-Door Hinges; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The main objects of my invention are to prevent the dropping or abrupt opening of stove-doors and consequent strain upon their hinges and connections, to automatically close or assist in closing such doors, and to limit their opening at the desired point.

It consists of certain peculiarities in the construction of hinges and their connections designed to accomplish the foregoing objects, as hereinafter particularly described, and pointed out in the claims.

In the accompanying drawings like letters designate the same parts in the several figures.

Figure 1 is a front elevation of a stove or oven door and the associated parts to which my improvements are applied. Fig. 2 is a horizontal section on the line 2 2, Fig. 1. Fig. 3 is an enlarged vertical section on the line 3 3, Fig. 1, showing the position of the hinge when the door is closed. Fig. 4 is a similar section showing the door open; and Fig. 5 is a vertical section on the line 5 5, Fig. 1.

A designates a stove, oven or range door having its hinges at the lower edge and opening downwardly. It is cast or otherwise formed with semicylindrical trunnions *a a*, formed with longitudinal wings *a' a'*, as clearly shown in Fig. 5.

B represents the door frame or plate of the stove or range, formed or provided on opposite sides of and at the bottom of the door-opening with semicylindrical or elliptical seats or bearings *b b*, as clearly shown in Fig. 4, for the trunnions *a a*.

C are leaf-springs attached to the sides of the door frame or plate by means of plates or castings D D placed over their upper ends and secured to said door-frame by screws or

bolts *d d*. These springs extend at their free ends over and are preferably slightly bent around the trunnions *a a*, as shown in Fig. 5. Pressing against the outer sides of said trunnions, they serve as keepers to hold them in place in their bearings *b b*, and by engagement with the wings *a' a'* tend to hold the door either open or closed and to prevent its abrupt dropping or opening, and thereby breaking or straining the hinges and their connections. They also serve to automatically close or assist in closing the door.

The castings D D are preferably recessed on the back between the ends, as shown in Figs. 4 and 5, in order to concentrate the bearing at their lower ends against the springs, and thus clamp them firmly to the door-frame at these points. They are preferably formed at their lower ends with extensions overhanging the springs and provided with screws *d' d'* for adjusting the tension of said springs or causing them to bear with more or less force against the trunnions of the door.

To stop the door when it is opened in a horizontal position or in a position approximately at right angles to the door frame or plate, I may form one or both of the trunnions with arms *e e*, and the door frame or plate with lugs or projections *f f*, arranged in the path of said arms.

The bearings *b b* are made elliptical or elongated to allow a slight vertical play of the trunnions for the purpose of permitting the ears or projections *g g* on the door to pass over and into engagement with the beveled notched projections *h h* on the door-frame or to allow for the engagement and disengagement of such latch or fastening as the door may be provided with.

By reference to Fig. 5 it will be seen that when the door is closed the springs C, pressing against the outer flat side of the wings *a'*, tend to retain the door in that position, and by reference to Fig. 4 it will be seen that when the door is open to the full extent said springs, bearing directly against the outer edges of said wings in a plane perpendicular to the axis of the trunnions, will tend to hold the door in that position. As the wings are turned from the position in which they are shown in Fig. 5 to that in which they are

shown in Fig. 4, the springs C C are thereby strained and tend to check the movement of the door; but by their resiliency they assist to close the door when it is swung in the opposite direction. If they are made of sufficient stiffness they will automatically close the door, especially when it is hung at one side and arranged to swing horizontally.

Although I have shown my improvements applied to a drop or downwardly-opening door, and they are particularly adapted thereto, they may be employed to advantage with horizontally-swinging doors.

Various changes in minor details of construction may be made within the intended scope of my invention.

I claim—

1. The combination with a door frame provided with open bearings, of a door provided with trunnions adapted to turn in said bearings and formed with wings, and springs secured at one end to said door frame and projecting over and pressing at their opposite ends against said trunnions and holding them in their seats, substantially as and for the purposes set forth.

2. The combination of a vertically swinging door provided with semi-cylindrical trunnions having laterally projecting longitudinal wings, a door plate or frame provided on the upper side with a beveled notched projection adapted to engage said door and hold it closed, and on the under side with vertically elongated seats or bearings for said trunnions, and springs attached at one end to said door frame and projecting at their free ends over and pressing against the outer sides of said trunnions and holding them in

their seats, substantially as and for the purposes set forth.

3. The combination of a stove door provided with trunnions having wings and arms, a door frame or plate provided with open bearings in which said trunnions are loosely seated and with lugs or projections in the paths of said arms, and springs attached to said door plate or frame and extending at their free ends over and pressing against said trunnions and holding them in their bearings, substantially as and for the purposes set forth.

4. The combination of a stove door provided with trunnions having wings, a door plate or frame provided with bearings in which said trunnions are loosely seated, and springs attached at one end to said door frame by clamping plates which are screwed to the door frame, and projecting at their free ends over and engaging with said wings, substantially as and for the purposes set forth.

5. The combination of a stove door provided with trunnions having wings, a door frame having seats in which said trunnions are loosely seated, springs bearing at their free ends against the outer sides of said wings, and clamping plates secured over the opposite ends of said springs to said door frame or plate and provided with adjusting screws in extensions overhanging said springs, substantially as and for the purposes set forth.

In testimony that I claim the foregoing as my own I affix my signature in presence of two witnesses.

ALFRED E. DETWILER.
